UNITED STATES PATENT OFFICE.

DAVID F. HENRY, OF ALLEGHENY, PENNSYLVANIA.

CAR-TRUCK.

SPECIFICATION forming part of Letters Patent No. 551,963, dated December 24, 1895.

Application filed October 1, 1894. Serial No. 524,590. (No model.)

To all whom it may concern:

Be it known that I, DAVID F. HENRY, a citizen of the United States, residing at Allegheny, in the county of Allegheny and State 5 of Pennsylvania, have invented certain new and useful Improvements in Car-Trucks; and I do hereby declare the following to be a full, clear, and exact description of the invention, such as will enable others skilled in the art to 10 which it pertains to make and use the same, reference being had to the accompanying drawings, which form a part of this specification, in which—

Figure 1 indicates a side elevation of my improved car-truck. Fig. 2 is a plan of the same. Fig. 3 is an end view of the same, showing axle-box in vertical section. Fig. 4 is a side elevation of a modification of the same. Figs. 5 and 6 are respectively plan view showing 20 horizontal section of axle-box, and end view showing vertical section of axle-box.

My invention relates to car-trucks, especially to trucks adapted to cars for use upon street-railways.

25 My object is, first, to produce a truck, by the use of which a longer or more extended wheel-base may be used, and consequently a longer car-body than at present possible without resorting to double trucks to support the 30 same, and at the same time to so construct the same as to prevent buckling or bowing at the middle usual in car-bodies mounted on the single trucks at present in use; second, to minimize or to entirely avoid the excessive 35 friction upon the wheels and axles and strain on the truck occasioned by the use of the present rigid axle-bearings, and, third, to produce a truck by the use of which the greatest possible evenness and ease in riding is attained 40 and jolting avoided, and to this purpose consists of the novel construction and arrangement of parts hereinafter described, reference being had to the accompanying drawings, forming part hereof, in which like letters indicate like parts wherever they occur.

45 Referring to said drawings, 1 1 are car-wheels, the axles 2 of which are journaled in the boxes 3, which are mounted in the pedestal 4, upon the top of which is bolted or 50 otherwise secured the truck-frame 5.

6 6 are brace-rods, the upper ends of which are bolted or otherwise secured upon the

truck-frame at either side the wheels, the lower ends of said rods, respectively, being bolted to the outer and inner sides, respectively, of said pedestal near the bottom thereof. 55 A plate or hanger 7 is rigidly secured to said brace-rods 6 6 on either side the wheels, the lower ends of the links 8 8 being connected to said plate or hanger, and the upper ends of 60 said links being connected to the outer ends of the semielliptical springs 9, which are mounted on the top of said axle-boxes, being secured thereto by the plates 10, which are bolted or otherwise secured upon the top 65 of said boxes, whereby said truck-frame and the car-body mounted thereon are supported by the ends of said springs. The axle-boxes are mounted in said pedestal 4 in such manner as to permit said boxes to move or reciprocate longitudinally and vertically, the longitudinal reciprocating movement of said boxes, as shown by the dotted lines, being sufficient to enable the axles journaled therein to radiate in the arc of a circle in turning 70 sharp curves; or, in other words, to permit the axle box or boxes of the wheels turning the outer and larger radius of a curve to progress slightly in the direction of the travel of the car, while the axle box or boxes of the 75 wheels on the inner and smaller radius of the curve remains stationary or retrogrades proportionally, whereby the axle is enabled to swing in the arc of a circle and to accommodate itself to exceedingly sharp curves, and 80 thus obviating the friction and strain upon the axle-boxes and pedestal occasioned by the use of rigid axle-boxes in turning curves, the vertical movement of the axle-boxes enabling the truck to accommodate itself to ordinary 85 and excessive loads. The links to which the 90 ends of the springs are connected enables said springs to progress longitudinally or move backward and forward in unison with the axle-boxes.

95 11 is a brace-rod extending on either side the wheel-base, the ends thereof being connected to the plate 4.

In Figs. 4, 5, and 6 I show a modification of my invention in which are shown the wheel-base carried on the springs 9, which instead of being mounted upon the top of the axle-box are mounted substantially in a similar manner upon the bottom thereof, the links se-

cured in the brace-rods 11 producing what I call a "lower suspension-truck," otherwise being substantially the same as heretofore described.

5 Having described my invention, what I claim, and desire to secure by Letters Patent, is—

In a car truck substantially as described, the combination of a frame, pedestals connected thereto, axle boxes mounted in said pedestals and adapted to reciprocate longitudinally and vertically therein, semi elliptical springs mounted upon said axle boxes,

brace bars connecting said frame and pedestal, and links the lower ends of which are connected to hangers, secured in said brace rods, the upper ends thereof connected to the ends, of said elliptical springs, substantially as described.

In testimony that I claim the foregoing I 20 hereunto affix my signature this 25th day of September, A. D. 1894.

DAVID F. HENRY. [L. S.]

In presence of—

WM. L. MONRO,
JNO. H. RONEY.
